UNITED STATES PATENT OFFICE.

EMIL BÖHM, OF BERLIN-KARLSHORST, GERMANY.

KEY RING.

1,412,011.

Specification of Letters Patent.

Patented Apr. 4, 1922.

Application filed July 9, 1920. Serial No. 395,180.

To all whom it may concern:

Be it known that I, EMIL BÖHM, citizen of the German Republic, residing at Berlin-Karlshorst, Germany, have invented certain new and useful Improvements in a Key Ring, (for which I have filed an application in Germany Mar. 30, 1916,) of which the following is a specification, reference being had therein to the accompanying drawing.

10 The known key-rings serving for the reception of a bunch of keys, have the drawback that, when turning one of said keys in its keyhole, the whole key-ring with the remaining bunch of keys must participate in said turning movement, which is rather inconvenient particularly with a large bunch of keys.

20 To overcome this drawback, the present invention provides a swivel-connection between the key-ring and each single key, so that the latter can be turned in its keyhole without the whole key-ring with the remaining bunch of keys participating in said movement.

25 The accompanying drawing shows a plan view of the improved key-ring.

a is the key-ring proper, which is split in a way known in the art for a detachable at-

tachment of a plurality of small rings *c* thereto, two such rings *c* being shown in the example, though any desired number of rings *c* may be used. Each ring *c* carries another small ring *e* by means of a swivel-connection *g*, each of said rings *e* serving for the reception of a key (not shown), which may be attached thereto in a way known in the art.

30 By these means, each key can be turned in its keyhole without the whole key-ring with the remaining bunch of keys participating in said movement.

35 Obviously, the rings *c* may be omitted, in which case the swivels *g* are attached directly to the key-ring *a*.

What I claim is:—

40 A key-ring comprising, in combination, a large split-ring, and a plurality of key holding rings having each a swivel-connection with said split-ring, substantially as and for the purpose set forth.

45 In testimony whereof I affix my signature in the presence of two witnesses.

EMIL BÖHM.
